BRAKE SHOE RETAINER KEY

Grant H. Arrasmith, Pearl River, N. Y., assignor to American Brake Shoe Company, New York, N. Y., a corporation of Delaware

Application November 30, 1955, Serial No. 550,082

1 Claim. (Cl. 188—243)

This invention relates to retainer keys for connecting a railroad brake shoe removably to the brake head.

Brake shoes of the kind used for braking railway equipment are conventionally attached to a brake head supported at one end of a brake beam so as to be disposed opposite the tread of the car wheel, and such attachment is attained by a key that enables the shoe to be removably or detachably associated with the brake head. The relation of the parts is such that the brake shoe hangs in a vertical relation, with the head of the key uppermost and the lower end of the key projecting beyond the lower end of the brake shoe and the brake head. In removing the key prior to disassociation of the brake shoe and the brake head, it is conventional to strike the lower end of the key with a hammer or the like to drive the key out of its home position. There are, however, situations where this cannot be easily accomplished, because the particular type of railway equipment does not permit a hammer to be manipulated in this way. For example, in the usual freight truck with inside hung brake shoes the clearances do not permit easy removal of the key in the manner mentioned above.

The primary object of the present invention is to adapt the upper end of the brake shoe key, that is, the end having a head, for removal by means of a standard pinch bar. Particularly, the object of the present invention is to provide ratchet teeth or like serrations along the longitudinal side walls of a brake shoe retainer key so that the end of a pinch bar or similar tool may be engaged therewith to remove the key by leverage.

Other and further objects of the present invention will be apparent from the following description and claim and are illustrated in the accompanying drawing which, by way of illustration, shows a preferred embodiment of the present invention and the principle thereof and what I now consider to be the best mode in which I have contemplated applying that principle. Other embodiments of the invention embodying the same or equivalent principles may be used and structural changes may be made as desired by those skilled in the art without departing from the present invention and the purview of the appended claim.

In the drawings:

Fig. 1 is a sectional view in part showing the assembled relation of the brake head, the brake shoe, and the retainer key;

Fig. 2 is a side elevation of a retainer key constructed in accordance with the present invention;

Fig. 3 is a rear perspective view of the key shown in Fig. 2;

Fig. 4 is a plan view of the key on an enlarged scale; and

Fig. 5 is a sectional view taken on the line 5—5 of Fig. 4.

The present invention is illustrated in Figs. 1 to 5 as embodied in a brake shoe key 9, and this key is adapted to be inserted into a keyway afforded by cooperating sections of a brake head 10 and an associated brake shoe 11

2

of conventional construction. Thus, the head 10 is provided with a pair of spaced apart U-shaped lugs 12 and 13 which project outward from the forward face or side of an arcuate plate 14 that is integral with the head. The lugs 12 and 13 afford aligned openings 12' and 13' which cooperate in affording in part a keyway for the key 9 as will be described below.

The shoe 11 is arcuate in vertical section as will be observed in Fig. 1, and projecting from the arcuate back thereof are a pair of end stops 17 and 18. Cooperating with the end stops 17 and 18 are toes 19 and 21 at corresponding ends of the head 10. Formed medially in projecting relation on the back of the shoe 11 is a U-shaped attaching lug 20, and the rear portion of the opening 20' afforded by this lug is adapted to be aligned with the openings 12' and 13' to complete the keyway section between the head 10 and the shoe 11.

As shown in Figs. 2, 3, and 4, the key 9 includes an elongated shank 22 having flat front and rear faces, and relatively narrow sidewalls 40 and 41 disposed in planes generally normal to the surfaces or planes of the front and rear faces of the shank 22. The key 9 is preferably made of relatively strong steel, and at one end, that is, the upper end as viewed in Fig. 1, the key 9 is provided with a head 23 bent at right angles relative the shank 22. The head 23 enables a blow to be delivered to the upper end of the key 9 when driving the key 9 to home position between the brake head 10 and the shoe 11.

Intermediate the head 23 of the key 9 and the opposite or lower end 25 thereof, the key is bowed or warped so as to provide an arcuate portion 26. This arcuate portion 26 of the key is adapted to engage the inner face of the base of the lug 20 as shown in Fig. 1. Thus, in driving the key 9 to its home position, the arcuate portion 26 is placed under compression.

Between the arcuate portion 26 and the head 23 of the key, a rib 28 is provided on one face of the key for the purpose explained in U. S. Patent 2,138,196. Spaced below the rib 28 at the lower end of the arcuate portion 26, the shank of the key is provided with an angle offset 30, and this offset when the key is in fully inserted position as shown in Fig. 1 is disposed below the lower end of the lug 13 of the brake head so as to afford an abutment tending to prevent accidental displacement of the key 9 from operative position. The shank 22 of the key 9 is made slightly arcuate in the portion 31 that is between the offset 30 and the lower end 25 of the key. When the key is placed under compression as described above, the lower arcuate portion 31 of the key 9 engages the lower edge of the plate 14, and in this manner the head 10 and the shoe 11 are stressed in opposite directions by the compressed key 9, thereby holding the related brake parts together in a fixed manner. In this connection, it will be observed that the lower end portion of the key 9 is provided with a series of serrations 35 any one of which is adapted to abut the lower edge of the plate 14 as shown particularly in Fig. 1. Thus, the serrations 35 constitute lugs adapted to operatively engage the lower edge of the plate 14 tending to assure that the key 9 remains in home position.

Ordinarily a key of the foregoing kind is removed from position between the brake head 10 and the brake shoe 11 by a hammer blow delivered to the lower projecting end 25 thereof. There are situations, however, where this cannot be easily accomplished, and in view of this I have provided teeth 36 on either side walls 40 and 41 of the key 9 in the portion intermediate the head 23 and the arcuate back portion 26 thereof. Each tooth 36 is defined by a flat shoulder 36S extended inwardly of the related side wall of the key shank from a line perpendicular to the planes of the front and rear faces of the key shank. Moreover, each shoulder 36S presents

a surface inwardly of the related side wall and disposed in a plane generally perpendicular to the related side wall to enable a withdrawing force to be effectively exerted on the key, as will be described, and the side walls of the key shank are further provided with sloped surfaces 36L which expose and afford hollows between the tooth surfaces 36S. Thus, when the key 9 has been driven home to the extent that the off-set 30 is disposed below the lower edge of the lug 13, the tooth elements 36 are exposed at the upper end of the key 9 in the area where the head 23 of the key is disposed between the upper ends of the related brake parts. These teeth enable the end of a pinch bar to be operatively engaged with the upper end of the key 9 so that by applying a downward force to the opposite end of the pinch bar the key 9 may be lifted or jacked while the inner end of the pinch bar is engaged with one of the tooth elements 36. This is of particular advantage in freight cars having trucks provided with inside hung brake shoes where there is generally an opening through which the pinch bar may be passed to engage an exposed tooth or serration 36 at the upper end of the key 9.

Hence, while I have illustrated and described the preferred embodiments of my invention, it is to be understood that these are capable of variation and modification, and I therefore do not wish to be limited to the precise details set forth, but desire to avail myself of such changes and alterations as fall within the purview of the following claim.

I claim:

A brake shoe key for coupling a brake head part and

a brake shoe part and comprising a relatively flat, elongated shank having at one end a head adapted to be impacted to drive the key forwardly into a keyway afforded by complementary sections on the brake head and the brake shoe, said shank having opposed front and rear faces and relatively narrow opposed side walls disposed in planes generally perpendicular to the planes of said faces, one of said faces including an arcuate portion between the opposite ends thereof adapted to be placed under compression by engagement thereof with one of said sections when the key is in the keyway, the end portion of the key shank adjacent said head being provided along at least one of said walls with a series of indented serrations which extend from the front to the rear face of said key shank at said end portion of said key shank and which are adapted to be selectively engaged by the end of a tool acting as a lever for forcing the key out of the keyway, each such serration including a shoulder extended inwardly of the related side wall from a line generally perpendicular to the planes of said front and rear faces of said shank, and each such shoulder affording a surface disposed in a plane generally perpendicular to the plane of the related side wall of the key shank.
